Patented Nov. 25, 1919.

Inventor,
Minor T. Holliday,

Minor T. Holliday
Attorney.

UNITED STATES PATENT OFFICE.

MINOR T. HOLLIDAY, OF BOZEMAN, MONTANA.

TOOTH-BRUSH.

1,323,057.

Specification of Letters Patent. Patented Nov. 25, 1919.

Application filed March 30, 1918, Serial No. 225,809. Renewed April 24, 1919. Serial No. 292,421.

To all whom it may concern:

Be it known that I, MINOR T. HOLLIDAY, a citizen of the United States, residing at Bozeman, in the county of Gallatin and 5 State of Montana, have invented certain new and useful Improvements in Tooth-Brushes, of which the following is a specification.

My invention relates to a brush of the 10 rotary type and particularly to a tooth brush in which the brush head revolves so as to brush the teeth vertically or "up and down" as science has found to be the preferred method.

15 The aim of the invention is to generally improve the construction of a brush of this kind; provide one of such form that the bristles may effectively extend between the teeth during a cleansing operation; and 20 particularly one having the spring and gearing for imparting rotary motion to the brush head, employing a rack bar pivoted to a depressible operating bar so that the rack bar need not move longitudinally of the 25 brush, and the operating bar movable longitudinally of the brush instead and at one end slidably connected to the brush in the particular manner hereinafter described and claimed.

30 Servient objects will appear as the following description progresses, being taken in connection with accompanying drawings, illustrating one preferred embodiment and wherein:—

35 Figure 1 is a side elevation of the tooth brush constructed in accordance with my invention;

Fig. 2 is a longitudinal sectional view of the same;

40 Fig. 3 is a top or plan view of the improved tooth brush;

Fig. 4 is a cross sectional view on the line 4—4 of Fig. 1;

Fig. 5 is a view of the tooth brush from 45 the handle end, showing the operating member depressed and its normal position suggested by dotted lines;

Fig. 6 is a cross sectional view on the line 6—6 of Fig. 1, and

50 Fig. 7 is a fragmentary longitudinal sectional view of the tooth brush on an enlarged scale, particularly illustrating the

means of connection between the operating member and the handle.

Referring specifically to the drawings, 55 the brush head comprises bristles or tufts 8 which extend from a cylinder 9 of celluloid or other suitable material. It will be noticed that this brush head has a substantially solid peripheral brush surface and a 60 substantially solid brush surface at one end. In any suitable manner, the sleeve 9 or other form of brush head which may be employed, is fastened to a rod or shaft 10.

Said shaft 10 is rotatably mounted in a 65 casing 11, being held in place by means of a washer or disk 12 which engages one end wall of the casing and by means of a spur gear wheel 13, preferably removably keyed to the shaft 10 and which abuts another 70 wall of the casing as shown in Fig. 2. Washer 12 and the gear wheel 13, therefore mount the shaft and brush head against longitudinal displacement, but removably, so that the brush head or brush head and 75 shaft, may when desired be inspected, repaired, discarded or replaced.

At the brushing end, the handle 11 has a guard at 14, which extends over the brush, and in use, engages the gums to avoid undue 80 contact with the bristles. In some instances, the brush head may be loosely mounted on the rod 10 and to this end, a lug 15 is formed integral with the guard 14, and depends therefrom so as to overlap the brush 85 head as shown in Fig. 2 and prevent longitudinal movement thereof in one direction. The disk 12 and adjacent wall of the handle will prevent longitudinal movement of said brush head in the opposite direction. 90

Gear wheel 13 is turned so as to rotate the brush head, through sliding movement of a bar or rack 16 having teeth meshing with teeth of this gear wheel. This rack 16 is preferably pivoted to a normally inclined bar or operating member 18, whose upward movement is limited by its engagement with an inclined wall 19 of the handle. Said handle at its operating end is cut away to provide a recess 20 into which 100 the bar 18 may be depressed and into a recess 21, deeper than the recess 20 and with which the recess 20 communicates. The inclined wall 19 and the recess 20 lead to a

further recess 22, whose base wall coincides with that of recess 20 and which has a restricted entrance at 23 and a vertically disposed stop wall at 24.

5 It will be noted that the operating member 18 has an arcuate or otherwise curved portion 25, at the free end of which, is bent into a lug 26. In mounting the operating member, the end 25-26 is thrust into the recess 20, against the wall 19, which serves to somewhat straighten the portion 25 and permit the lug 26 to slide through the entrance 23 and past the wall 24, whereupon the inherent resiliency of the portion 25 15 will restore the portion to normal shape so that the operating member cannot easily be withdrawn from the recess 22 and especially will not accidentally become detached in view of the fact that the lug 26 will engage 20 the wall 24 upon movement of the operating member away from the brush head.

An L-shaped closure is provided for the recess 21 having a vertical wall 27 to serve as one end of said recess and having a foot 25 28 riveted or otherwise fastened to the handle 11 as at 29. An expansive coil spring is employed to normally maintain the operating member 18 raised or in the position shown in Fig. 2 and to restore it to that position after depression. This spring is indicated at 30 and is fastened in place in any suitable manner. For instance, it may be soldered as at 31 to the operating member 18 and as at 32 to the foot 28. Operating member 18 may be bent downwardly into a guard 33 to provide a smooth surface at the outer terminal of the operating member and also to avoid contact of the operator's hand with the spring 30.

40 It will be understood that in use, the brush head is used for the same purposes as the present brush heads of tooth brushes. One hand of the operator grasps the handle 11 and the operating member 18, alternately closing and opening the hand so as to depress the operating member 18 against the tension of spring 30 and then release it so that the spring 30 may restore it to normal position for the next depression. During 45 this movement of the operating member 18, the bar or rack 16 slides vertically, but not horizontally, turning the gear wheel 13, the shaft 10 and accordingly the brush head. As rack 16 moves downwardly, the operating member 18 of course slides into the recess 22 toward the brush head. Upward movement of the operating member, cannot move the bar 16 longitudinally nor displace the member, in view of the fact that the 50 wall 24 is in the path of movement of the lug 26. In its depressed position, the operating member 18 is disposed in the recess 20 as suggested by Figs. 2 and 7.

I might mention the fact that the handle 60 65 11 may be made of any suitable material

but that I preferably desire to make it from celluloid inasmuch as it is a white material and can be used advantageously from the standpoint of ease and cost of manufacture.

Changes in the details of construction may 70 be resorted to without departing from the spirit and scope of the invention provided they fall within the terms of the appended claims.

I claim:—

1. A motive apparatus having a handle, turnable driven means having an operating member movable transversely thereof, and means to mount the operating member for sliding movement longitudinally of the handle during its transverse movement. 80

2. A motive apparatus having a handle, a bar, an operating member to which the bar is pivoted, depressible to move the bar transversely of the handle, driven means rotatable through said transverse movement, and means to mount the operating member for sliding movement longitudinally of the handle during its transverse movement. 85

3. A motive apparatus having a handle, 90 rotatable driven means comprising a depressible operating member, said handle having an inclined wall, means to urge the handle into engagement with said wall, and means to permit sliding movement and prevent displacement of the operating member relatively to said wall. 95

4. A motive apparatus having a handle, said handle having a wall, driven means having an operating member, said operating member extending past said wall and movable longitudinally relatively thereto, and means on the member to abut the wall to prevent displacement of the member. 100

5. A motive apparatus having a handle, 105 said handle having a wall and a restricted passage-way to the wall, turnable driven means having an operating member, said member being compressible to permit passage through the restricted passageway, and a lug on the compressible portion opposite said wall, said wall being in the path of the movement of the lug to prevent accidental retraction of the operating member through the passageway. 110

6. A motive apparatus having a handle, a driven shaft journaled in the handle, said handle being cut away, a gear wheel disposed in said cut-away portion and fixed on the shaft, said handle having an inclined wall at the cut-away portion, a recess to which the wall leads, the handle having a stop wall within the recess and a restricted passageway to the recess, a rack bar having teeth in mesh with those of the gear wheel, 120 an operating member, said rack bar being pivoted to the operating member, a closure member for one end of the cut-away portion, means to fasten the closure member to the handle, a spring secured to said closure 125 130

member and to the operating member urging the operating member into engagement with the inclined wall, said member having a compressible portion to permit passage of 5 one end thereof through the restricted passageway, and a lug within the recess extending from the compressible portion, said wall of the recess lying in the path of move-

ment of the lug to prevent retraction of the operating member from the recess.

10

In testimony whereof, I have affixed my signature in the presence of two witnesses.

MINOR T. HOLLIDAY.
